FREDERICK L. BICKEL, OF IVYLAND, PENNSYLVANIA.

DYEING-MACHINE.

1,344,788.

Specification of Letters Patent. Patented June 29, 1920.

Application filed May 31, 1919. Serial No. 300,846.

To all whom it may concern:

Be it known that I, FREDERICK L. BICKEL, a citizen of the United States, residing at Ivyland, in the county of Bucks and State 5 of Pennsylvania, have invented certain new and useful Improvements in Dyeing-Machines, whereof the following is a specification, reference being had to the accompanying drawings.

10 The invention relates to machines adapted for dyeing, bleaching, carbonizing, washing or otherwise treating textile fabrics, or materials.

15 The invention is more particularly directed to a machine of the above class comprising means whereby the material under treatment, is caused to be periodically compressed and relaxed so as to alternately expel and absorb the treating liquor; means 20 whereby the material is subjected to a slight abrasive action and its position constantly shifted to vary the surface exposed to abrasion; and means whereby the treating liquor is caused to circulate, so that a thorough 25 permeation of the material is effected.

To this end, the machine which I have invented consists of a vat within which oscillates a diaphragm whereby the material under treatment is periodically lifted from the 30 treating liquor and at the same time compressed to expel part of the absorption.

35 The bottom of the vat is curved in substantial concentricity with the center of oscillation of the diaphragm, and supplemented with a perforated, corrugated, abrasive lining, which is spaced from the vat bottom to afford a by-pass or channel whereby the treating liquor may flow from one side of the diaphragm to the other during its 40 oscillation. Interposed in said channel is a check valve, which not only determines the direction of flow of the liquor, but is further functional in causing the latter to rise upon one side of the diaphragm and flow over the 45 top of the same, and onto the material, thereby setting up an effective circulation.

The organization which is typical of my invention, and wherein the elements above outlined are incorporated, will be best understood from the following detailed description.

In the accompanying drawings, Figure I, is an end elevation of a dyeing machine conveniently illustrating my invention, and

Fig. II, is a cross sectional view of the 55 same.

In its preferred form, my invention consists of a receptacle or vat 1, whose cross sectional configuration, as best seen in Fig. II, is substantially that of a quadrant. This 60 vat is constructed of a non-corrodible material, preferably wood, so as to better resist the action of the various chemical solutions ordinarily employed in the arts of dyeing, bleaching, etc. The structure is 65 bounded at its ends, by walls 2, which serve, through the instrumentality of stay rods 3, to sustain between them, the longitudinal rear wall 4, and the curved bottom 5, the latter terminating at the front of the machine, at a level somewhat above its vertical center. The vat is closed by a cover consisting of a fixed section 6, extending about half way across the top, and supplemented with a movable section 7, mounted to swing 70 about a hinged connection indicated at 8. The movable cover section is provided with a longitudinal perpendicular front board 9, the lower end of which is adapted to seat upon the ledge afforded by the top end of 75 the curved bottom as shown in Fig. II. Thus, when the cover is in its lowered position, the board 9, forms in effect, a continuation of the curved bottom 5, thereby completely closing the front of the vat. In order to afford the necessary rigidity, the board 9, is braced by means of a number 80 of metal angles or brackets one of which is shown at 10.

The bottom of the vat is jacketed to provide a by pass or channel 11, for the dye liquor circulation, as will be more definitely explained later. The subdivision is effected by a corrugated sheet metal lining or false bottom 12, suitably spaced from the curved 85 bottom and having its ends wrapped about tubular supporting bars 13 and 14, which run longitudinally of the structure and are appropriately secured in its end walls. At its lower terminus, the passage 11, communicates with the interior of the vat through an opening 16, subject to the automatic control of a check valve 17, which is fulcrumed about the bar 13. The troughed channels 18, of the corrugations are pierced by a series of drain apertures as clearly shown at 19, in Fig. II.

In the course of the treating operation, as

practised according to my invention, the material under treatment represented conventionally at M, in Fig. II, is subjected to the action of an oscillating diaphragm 20, suspended by means of arms 21, from a rock shaft 22. Said shaft is journaled in the end walls of the vat at a point somewhat forward of the rear wall 4, with the resulting formation of an interspace 23, behind the diaphragm. During oscillation, the lower end of the diaphragm 20, moves very close to the corrugated bottom working surface afforded by the lining 12, a slight variation being however established by virtue 5 of the eccentricity of the rock shaft 22, with respect to the center of curvature of said lining or partition 12. Thus in swinging upward toward the position indicated in dotted lines in Fig. II, (the normal limit 10 of oscillation) the outer end of the diaphragm 20, moves a little farther away from the lining, so as to prevent the material from being pinched between the end of said diaphragm and the ridges of the corrugations.

The diaphragm is supplemented at its upper and lower edges, with inward projections 25 and 26, respectively adapted to engage the mass of the material under treatment. Said diaphragm is also provided near its top with a series of apertures 27, for the passage of the treating liquor, the normal level of which is indicated at 28, in Fig. II.

As a means for actuating the diaphragm, I have arranged a driving mechanism which will be best understood from Fig. I. This mechanism includes a main shaft 30, which may be driven from any suitable source of power, and in turn imparts rotation, 30 through a pinion 31, to a gear 32. Said gear is supplemented with a crank pin 33, connected by a link 35, with a slide block 36, adjustably set upon an arcuate arm 38, which is fixed to the protruding end of the rock shaft. Said arm has its center of 40 curvature co-incident with the axis of rotation of the crank gear 32 when the arm is in the retracted position shown. The various adjustments of the block are fixed by 45 a hand screw 37. By the provision of an arrangement such as above set forth, the amplitude of oscillation of the diaphragm may be varied according to the requirements of the particular use to which the machine 50 is to be put in practice. Furthermore, by virtue of the peculiar curvature of the arm 38, the latter will always come to the limit of its retracted movement in the illustrated 55 position regardless of the position of block 60 36, on said arm.

The device is also provided with auxiliaries such as a perforated steam pipe 39, extending longitudinally of the vat and serviceable for boiling or heating purposes; 65 and an outlet 40, for draining the vat; said

opening being provided with a suitable protective plug 41.

In order to facilitate the removal of the material from the vat after the treating operation is completed, I have provided a drop board 42, which is hinged about the bar 14, and may be swung downward to the inclined position illustrated in dot and dash lines in Fig. II. When the diaphragm is brought to rest in its uppermost position, said board 70 forms in effect, a continuation of the same so that the material may be rolled down the inclination without necessitating any actual lifting. In some cases where the nature of the material will permit, the machine 75 may be unloaded without actually stopping the same.

The operation of my invention is as follows:

As the diaphragm moves through the active portion of its oscillation, in urging the material forward and upward, the level of the treating liquor rises at the front of the diaphragm and drops at the rear of the same, the resulting difference of head causing 80 the displaced liquor to flow downwardly through the perforated lining and channel (the valve 17, opening automatically at this time) toward the rear of the diaphragm. If the liquor in the front of the diaphragm 85 rises above the openings 27, a portion of the same will also flow through said openings to the rear. As the liquor draws from the material mass, the latter, by virtue of its own weight under saturation, settles upon 90 the surface of the corrugated lining, thereby offering resistance to being moved by the diaphragm. As a consequence of the action, the lower surface of the material will be gathered and compressed by the co-action of 100 projection 26, with the corrugated lining into a series of plaits, thereby expelling the greater amount of the absorption, and the upper portion of the mass will remain comparatively relaxed. Notwithstanding the 105 resistive action of the corrugated lining, it is to be understood that the material mass as a whole is nevertheless shifted to a considerable extent.

The return movement of the diaphragm 110 causes the valve 17, to close, and the liquor on the rear side of said diaphragm to rise quickly, the excess flowing over the top of the diaphragm and openings 27, and onto the material. This action will continue until a state of equilibrium of the liquor is established upon both sides of the diaphragm for which purpose the openings 27, are more especially provided. As the diaphragm retracts, the material does not roll 120 back as might be expected, because the corrugated lining prevents any movement of that portion with which it is in direct contact, and therefore, the greater bulk left in a relaxed condition; as above noted, breaks or 125

divides substantially at the center of the mass and fills the intervening gap. This latter action is assisted by the cascading of the liquor over the top of the diaphragm as 5 already described.

From the foregoing, it will be seen that by the coöperation of the several associated elements, which constitute my invention, not only is the liquor caused to circulate through 10 the material, but the position of the latter is continuously shifted and at the same time subjected to a compressive action, which insures thorough permeation without causing any tangling and injury resulting directly therefrom. This is of the utmost importance in the treatment of delicate fabrics which will not stand the tumbling upon 15 which principle most dyeing machines operate.

20 After the action has progressed to the desired degree, the block 36 is shifted higher up upon the arcuate arm 38, and the machine brought to rest with the diaphragm in the position shown in dot and dash lines in 25 Fig. II. The hinged section 7 of the cover is then thrown open and the board 15 dropped to its lowered position whereupon the operative may readily remove the material and substitute a new charge therefor.

30 While the lining 12 has been shown and described herein as being corrugated, a plain perforated lining could be employed to equal advantage as far as the circulatory principle is concerned.

35 Having thus described my invention, I claim:

1. In a machine for treating fabrics or materials, the combination of a receptacle or vat for the treating liquor; and means for 40 compressing the material under treatment to expel a part of the absorption comprising a diaphragm adapted to oscillate in said vat and periodically move the material under treatment out of the treating liquor.

45 2. In a machine for treating fabrics or materials, the combination of a receptacle or vat for the treating liquor, said vat having a curved corrugated bottom working surface; and an oscillating diaphragm having 50 its outer end swinging substantially in concentric relation to the curved bottom working surface and adapted to compress the material under treatment in opposition to the resistance offered by said corrugated 55 working surface.

55 3. In a machine for treating fabrics or materials, the combination of a receptacle or vat for the treating liquor, said vat having a curved corrugated bottom working surface; an oscillatory diaphragm having 60 its outer edge swinging in close proximity to the corrugated bottom working surface, but in slight eccentricity with respect thereto, whereby when the diaphragm moves forward to compress the material against the

corrugations, its lower edge gradually recedes so as to prevent any pinching of the material.

4. In a machine for treating fabrics or materials, the combination of a receptacle or 70 vat for the treating liquor, said vat having the cross sectional configuration of a lower circle quadrant; and an oscillatory diaphragm swinging substantially in concentric relation with respect to the curvature of the 75 vat whereby the material under treatment is periodically moved out of the treating liquor, and at the same time compressed to expel a part of the absorption.

5. In a machine for treating fabrics or 80 materials, the combination of a receptacle or vat for the treating liquor, said vat having the cross sectional configuration of a lower circle quadrant, and having a corrugated interior working surface corresponding to the curved wall; an oscillatory diaphragm swinging substantially in concentricity with said curved surface and adapted to compress the material and at the same time shift the same upwardly along the 85 curved corrugated surface and out of the liquor, whereby, when the diaphragm is retracted, the corrugations sustain the portion of the material with which they are in contract, while the bulk of the material 90 divides and falls back into the liquor into the space cleared by said diaphragm.

6. In a machine for treating fabrics or materials, the combination of a receptacle or vat for the treating liquor; a diaphragm 100 adapted to lift the material under treatment from the treating liquor when moving in one direction; and coöoperative means whereby when the diaphragm moves in the opposite direction, the treating liquor is caused 105 to surge over the top of the diaphragm and onto the material.

7. In a machine for treating fabrics or materials the combination of a receptacle or vat for the treating liquor, said vat having a channeled bottom; an oscillatory diaphragm adapted to effect motion of the material in the treating liquor; and means whereby, when the diaphragm is moved in one direction, the liquor displaced is permitted to flow through said channeled bottom to the other side of the diaphragm, but when the latter moves in the opposite direction, the displaced liquor is caused to flow over the top of said diaphragm and 115 onto the material.

8. In a machine for treating fabrics or materials the combination of a receptacle or vat for the treating liquor, said vat having a curved bottom; a perforated lining concentrically spaced from said vat bottom to form a channel; an oscillatory diaphragm having its end swinging in close proximity to said lining; and a check valve interposed 125 in said channel whereby the liquor is per- 130

mitted to flow from one side to the other of the diaphragm when the latter moves in one direction, but which automatically closes when the diaphragm moves in the 5 reverse direction, whereby the liquid is caused to rise at the opposite side of the diaphragm and flow over the top edge of the same and onto the material.

9. In a machine for treating fabrics or 10 materials the combination of a receptacle or vat for the treating liquor; an oscillatory diaphragm for moving the material under treatment in said liquor; and means for varying the amplitude of oscillation of 15 said diaphragm without changing the limit of its movement in one direction.

10. In a machine for treating fabrics or materials, the combination of a receptacle or vat for the treating liquor; an oscillatory 20 diaphragm for moving the material under treatment in said liquor; means for varying

the amplitude of oscillation of the dia- phragm including a rock shaft from which 25 said diaphragm is suspended; an arcuate arm secured to said rock shaft; a slide block 30 adjustably set upon said arcuate arm; a crank; and a connecting rod interposed be- tween said slide block and crank, the center of curvature of said arm being coincident with the crank axis when said arm is in the 35 retracted position, whereby the limit of mo- tion of said arm in one direction is fixed notwithstanding the various adjusted pos- tions of said slide block.

In witness whereof, I have hereunto 36 signed my name at Philadelphia, Pennsyl- vania, this 13th day of May 1919.

FREDERICK L. BICKEL.
